HUMIDIFYING APPARATUS

Bruno Michalski, Paramus, N. J., assignor of one-half to Robert W. Beardslee, Scarsdale, N. Y.

Application May 15, 1935, Serial No. 21,532

5 Claims. (Cl. 237—78)

This invention relates to humidifying apparatus employing steam as a humidifying agent and has for its object to provide a humidifying arrangement in combination with a steam heating unit or radiator whereby humidification of the surrounding atmosphere can be effected regardless of whether the heating unit is under a pressure or a vacuum.

An important feature of this invention for all domestic, commercial and industrial purposes resides in the provision of means beyond the humidifying steam connection for retarding supply of steam to the heating unit or radiator so that sufficient pressure is maintained in the section where the humidifying connection is located to permit steam to flow to the atmosphere through the humidifying line. Preferably such retarding means comprises a suitable restriction placed either in the steam pipe between the usual steam control valve supplying the heating unit and the heating unit itself, or in an early section of said heating unit. The line supplying steam to the humidifying outlet may either be tapped off the section of the line between the control valve and the restriction or just ahead of the steam control valve, according to conditions. The effective area of the opening in the restriction is determined so as to maintain such a pressure above the atmosphere to be humidified as to cause a flow of steam through the humidifying line to that atmosphere. The effective area of the passage through the restriction can be fixed at a size suitable for the conditions under which it is installed; or it can be provided with means for adjusting the effective area of steam flow.

According to the invention the flow of steam to the heating unit may be controlled by a manually operated valve or by any suitable type of automatically or thermostatically controlled valve. In any of the methods of steam heat control the humidifying apparatus may have its supply of humidifying steam regulated either by means of a manually operated valve, by means of an automatic or humidistatic valve, or by means of a fixed opening or an adjustable opening. These methods of steam supply to the heating unit and to the humidifying apparatus may be used in any desired combination.

Another important feature of the invention resides in the provision of means for preventing the admission of air to the heating system through the humidifying apparatus when the steam is turned off from the unit to which the humidifying apparatus is attached or when it is turned off from the heating system itself.

These and other features and advantages of the invention will be described in connection with the accompanying drawings, in which:

Fig. 1 is an elevation showing the invention applied to a common system with hand controlled inlet valve and automatic outlet valve; 5

Fig. 2 is a further modification of Fig. 1 wherein the humidifying steam is taken from a radiator section;

Fig. 3 is a view similar to Fig. 1 wherein the inlet valve is thermostatically controlled; 10

Fig. 4 is a detail on an enlarged scale showing the restricted passage to the radiator employed in Figs. 1 and 3;

Fig. 5 shows a modification of the invention employing a valve in place of the restrictor of Fig. 4; 15

Fig. 6 is a further modification wherein the steam supply enters the top of the radiator instead of the bottom; 20

Fig. 7 is a detail sectional view similar to Fig. 4 but with means for adjusting the restrictor;

Fig. 8 is a view similar to Fig. 4 but with the restricted opening adjacent the bottom of the steam supply passage to the radiator; 25

Fig. 9 is an end view of Fig. 8; and

Fig. 10 is a view similar to Fig. 9 but with a modified form of restriction.

I represents a steam radiator of conventional type of one or more columns having a steam supply 2, controlled by hand valve 3 and return pipe 4 controlled by automatic valve 5 of conventional type actuated by a bellows or otherwise, opening when the radiator is cold to permit withdrawal of air and water of condensation, and closing when the radiator is hot to prevent waste of steam. 30

In Fig. 1, 6 is a humidifying pipe tapped into the steam supply of the radiator just beyond valve 3 and containing a hand cock 7, check valve 8 opening outwardly and humidifying discharge pipe 9 which may be perforated or otherwise arranged as desired. In case of objectionable drip, the end of pipe 9 can be provided with absorbent material such as asbestos, or such material can be put below the pipe 9 on the floor or on a pad on the radiator so as to be heated thereby. Such devices are well known and are not a part of this invention. 40

As shown in detail in Fig. 4, the steam flow to the heating unit such as radiator I is through a restricted opening 10 which has the effect of maintaining such a steam pressure in this section where the humidifying line is tapped off as to permit of steam flowing through the humidifying 45

line to the atmosphere. The check valve 8 prevents back flow of air or steam into the system through pipe 6 when valve 5 is open and there is vacuum in pipe 6.

5 In Fig. 2 the humidifying pipe 12 is tapped off the first radiator section, and in order to enable it to function a disc 13 with a restricted opening is placed between the first radiator section and the next. In this method the system 10 functions as previously described.

In Fig. 3 is shown a thermostatically controlled inlet valve 14 instead of hand valve 3. 15 is a bulb containing a volatile liquid or gas connected by tubing 16 to the valve 14. When the atmosphere surrounding the bulb and tubing is heated the volatile liquid or gas is also heated and expands, reducing the opening of valve 14, the latter opening to a greater extent when the bulb cools off.

20 Fig. 5 shows a modification of the invention in which a hand valve 19 replaces the restricted opening 10 of Fig. 4.

In Fig. 6 the steam supply enters the top of the radiator instead of the bottom; otherwise the 25 system is similar to Fig. 1.

Fig. 7 shows a modification of Fig. 4 wherein the restricted opening 10 is adjustable by means of a needle or screw valve 20.

The modification shown in Figs. 8 and 9 is similar to Fig. 4 except that the restricted opening 10 is adjacent the bottom of the steam supply 30 passage to the radiator. In Fig. 10 the arrangement is the same except that the restriction 10 is of substantially elliptical shape. The restriction 35 can be made with one or more openings, and the openings can be located as desired to meet conditions.

40 It will be seen from the above that the function of the restrictor on the inlet side of the radiator is to retard the flow of steam through the radiator so as to build up a pressure positive to the atmosphere in the humidifying steam discharge means and thereby permit discharge of steam through the humidifying outlet, thus humidifying 45 while the radiator is heating up. It is well understood that with proper humidity a room is more healthful and also that with a lower temperature a room is equally or more comfortable. Where the system is equipped with thermostatic 50 or automatic control of the inlet valve or steam supply, the invention is especially useful, and by equipping the humidifying steam line with a humidity controlled valve or humidistat both temperature and humidity control are automatically maintained.

55 It will be evident that various changes may

be made in the details of construction and operation disclosed herein without departing from the scope and spirit of the invention as defined by the appended claims.

The invention claimed is:

5 1. In combination in a heating system including a steam supply, a heating unit and a control valve therefor and a vacuum return, means beyond said valve for discharging humidifying steam to the atmosphere, and means beyond the 10 humidifying steam connection for retarding the flow of steam through said unit whereby a pressure positive to the atmosphere is built up in said discharge means.

15 2. In combination in a heating system including a steam supply, a heating unit and a control valve therefor and a vacuum return, means between said valve and said heating unit for discharging humidifying steam to the atmosphere, means beyond the humidifying steam connection for retarding supply of steam to said unit whereby a pressure positive to the atmosphere is built up in said discharge means, and means in the humidifying steam passage preventing back-flow of air into the system.

20 25 3. In combination in a heating system including a steam supply, an inlet valve, and heating unit, means between the valve and the heating unit for discharging humidifying steam to the atmosphere, and a restricted orifice beyond the 30 humidifying steam connection retarding supply of steam to said unit whereby a pressure positive to the atmosphere is built up in said discharge means.

35 4. In combination in a heating system including a steam supply, a heating unit and a control valve therefor, means between said valve and said heating unit for discharging humidifying steam to the atmosphere, and means including a restricted passage beyond the 40 humidifying steam connection and beyond said control valve for retarding supply of steam to said unit whereby a pressure positive to the atmosphere is built up in said discharge means.

45 5. In combination in a heating system including a steam supply, a heating unit and a control valve therefor, means beyond said valve for discharging humidifying steam to the atmosphere, means including a restricted passage beyond the 50 humidifying steam connection for retarding the flow of steam through said unit whereby pressure positive to the atmosphere is built up in said discharge means, and means for adjusting the restriction of said passage.

55 BRUNO MICHALSKI.
